DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

INTEGER PROGRAMMING METHOD FOR GEO-
GRAPHICALLY DISTRIBUTING IDENTICAL
RESOURCES**

Richard George Casey, San Jose, Calif., assignor to International Business Machines Corporation, Armonk, N.Y.

Continuation of application Ser. No. 292,007, Sept. 25, 1972. This application Aug. 17, 1973, Ser. No. 389,395

Int. Cl. G06f 9/12

U.S. Cl. 444—1

4 Sheets Drawing. 33 Pages Specification

A method for controlling a programmable digital computer to optimize the geographical distribution of identical resources with respect to a plurality of geographically separated users given the costs associated with storing said resource when located at each possible location and the costs associated with each user communicating with each possible location.

4 Sheets-Sheet 4

STORE ELECTRICAL SIGNALS REPRESENTING QUERY AND UPDATE
TRAFFIC FROM EACH POSSIBLE RESOURCE LOCATION, AND THE
COMMUNICATION COSTS

REPRESENT EACH POSSIBLE RESOURCE ALLOCATION AS A VERTEX ON
COST GRAPH, SAID VERTICES BEING INTERCONNECTED BY PATHS
REPRESENTING THE ADDITION OF A SINGLE RESOURCE TO THE PREVIOUS
ALLOCATION

CONTROL THE COMPUTER TO CALCULATE FROM SAID STORED SIGNALS THE
COST ASSOCIATED WITH THE VERTEX REPRESENTING THE ALLOCATION OF
A RESOURCE TO ALL POSSIBLE LOCATIONS

CONTROL THE COMPUTER TO CALCULATE THE COST ASSOCIATED WITH
EACH VERTEX REPRESENTING THE ALLOCATION OF A RESOURCE TO ALL
EXCEPT ONE POSSIBLE LOCATIONS

STORE ELECTRICAL SIGNALS REPRESENTING THE BEGINNING VERTEX,
SAID BEGINNING VERTEX REPRESENTING THE ALLOCATION OF RESOURCES
TO THOSE SAID EXCEPT ONE POSSIBLE LOCATIONS WHERE THE COST
ASSOCIATED WITH THE ALLOCATION OF A RESOURCE TO ALL EXCEPT ONE
POSSIBLE LOCATION IS GREATER THAN THE COST ASSOCIATED WITH THE
ALLOCATION OF A RESOURCE TO ALL POSSIBLE LOCATIONS

STORE ELECTRICAL SIGNALS REPRESENTING THE MAXIMUM NUMBER OF
PATHS TO BE TRACED IN PARALLEL FROM ONE LEVEL OF THE COST GRAPH
TO THE NEXT

CONTROL THE COMPUTER TO TRACE PARALLEL PATHS FROM SAID
BEGINNING VERTEX AND COMPUTE THE COST FUNCTION OF VERTICES ON
SAID PATH UNTIL THE COST FUNCTION INCREASES, CLUSTERING THE
PATHS SO THAT NO MORE THAN SAID MAXIMUM NUMBER IS TRACED FROM
ONE LEVEL OF THE COST GRAPH TO THE NEXT

STORE ELECTRICAL SIGNALS REPRESENTING THOSE VERTICES REPRESENTING
AN ALLOCATION OF RESOURCES HAVING A LOCAL OPTIMUM COST FUNCTION

WHEN THE COST FUNCTION HAS INCREASED ON EACH PATH BEING TRACED,
CONTROL THE COMPUTER TO SELECT FROM AMONG THE LOCAL OPTIMA
ALLOCATIONS THE BEST ALLOCATION

FIG. 7
